UNITED STATES PATENT OFFICE.

HENSON DAVIS, OF ROUNDUP, MONTANA.

MINER'S CARBIDE LAMP.

Application filed December 22, 1919. Serial No. 346,446.

To all whom it may concern:

Be it known that I, HENSON DAVIS, a citizen of the United States, residing at Roundup, in the county of Musselshell and State of Montana, have invented new and useful Improvements in Miners' Carbide Lamps, of which the following is a specification.

This invention relates to a carbide lamp for miners and the like and the principal object of the invention is to simplify the construction and increase the effectiveness of the light.

Another object of the invention is to lessen the liability of the stoppage of the water and gas ports and to provide means whereby these parts may be easily cleaned.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a longitudinal sectional view.

Figure 2 is a plan view.

Figures 3 and 4 are detail views.

As shown in these views the body of the lamp consists of the upper part 1 which forms the water chamber, the lower part 2 which forms the carbide chamber and the central part 3 which connects the two parts together and is screw threaded to receive the screw threaded neck of the carbide chamber 2.

The part 1 is provided with a reduced bottom part 1' which forms the shoulder on which the bottom plate 4 rests and the central part 3 is connected to or formed with this reduced part and the screw threads in this part 3 lead to the interior of this reduced part so that when the carbide chamber 2 is screwed home its upper end will pass into this space and thus prevent the screw threads from being choked with dust or dirt. If the female threads ended abruptly in part 3 the male threads on the carbide chamber would carry the dirt along to the closed end of the female threads and eventually this dirt would prevent the screwing

home of the carbide chamber so that the lamp would leak and a new gasket would

have to be used on the chamber. By my arrangement the dirt is carried to the space formed by the depending part 1' of the water chamber and the threads are kept clean.

A tube 5 passes centrally through the water chamber and has its lower end projecting well into the carbide chamber. This tube is provided with holes 5' so that the water may flow from the water chamber thereinto. A screw threaded stud 6 has screw threaded engagement with the upper end of the tube and this stud carries a handle 7 by which it may be rotated. The open lower end of the tube is controlled by the valve 8 which is carried by the stem 9, passing through the tube and having its upper end reduced and passing through the stud 6 and secured thereto by the nut 10. The lower part of the stem is provided with a three-sided enlargement 11, this part acting as a guide to the valve for giving it a proper setting which insures the uniform flow of water. By moving the handle in one direction to cause the stud 6 to move upwardly in the tube the valve will be raised to its closed position so as to prevent water dropping into the carbide chamber. By moving the handle in the opposite direction the stud will be lowered to open the valve.

An opening 12 is formed in the bottom plate 4 and a burner tube 13 has its inner end connected with said opening and this tube passes through the body of the lamp and is screw threaded to receive a screw threaded cap 14 which carries the burner tip 15. A reflector 16 is held to the burner tube by said cap. A cup-shaped piece of wire gauze 17 is connected with the bottom of the plate 4 and a disc 18 of felt or similar filtering material is placed over this gauze. This gauze acts to hold the filtering material away from the opening 12 and the bottom of the plate 4 and forms a chamber to receive the gas passing through the filtering material. I prefer to form a flange 18' on the disc of filtering material, which bears against the flange at the bottom of the reduced part 1' and receives the upper screw threaded end of the carbide chamber.

The upper part of the water chamber carries a filling plug 19 and supporting hooks 20 are carried by the body.

It will thus be seen that the water flowing through the holes in the tube from the water chamber will pass down through the tube

and through the space between the valve and the end of the tube and thus come in contact with the carbide. The resulting gases will rise in the carbide chamber and will filter 5 through the filtering material into the space formed by the gauze and the bottom of the plate 4. This gas will pass through the opening 12 into the burner tube, which is packed with filtering material, and will flow through 10 the burner tip.

Many times when the carbide in the lamp is only partly exhausted it will expand and some of the ash will be forced under the valve into the water tube so as to shut off 15 the flow of water. When this occurs in my lamp the handle is turned to permit the water to flow into the tube and then the knob on the end of the stem is turned backwards and forwards to cut the ash loose by 20 the corners of the enlarged part of the valve stem. The water will then wash the ash out. This operation can be carried out without disturbing the light. As the tube 5 will be 25 filled with water from its lower end to a point even with the water level in the tank the escape of gas through the tube will be prevented under ordinary conditions.

The filtering material acts to prevent damage to the lamp where the screw threaded 30 parts come together. It doesn't have to have a container to hold it in place as it fits in the reduced part below the bottom of the water tank. The gauze holding the filtering material away from said bottom forms a chamber 35 to receive the gas and allows a large part of the filtering material to act as a filter

instead of just that portion which covers the opening 12. The screw threaded end of the carbide chamber engaging the felt will keep 40 the felt in place and said felt acts to keep the threads clean.

By having the burner tip carried by a screw threaded cap the tip may be removed and the burner tube cleaned at any time. The packing in said burner tube prevents 45 the moisture being carried into the burner by the gas.

It is thought from the foregoing description that the advantages and novel features 50 of my invention will be readily apparent.

I desire it to be understood that I may make changes in the construction and in the combination and arrangement of the several parts, provided that such changes fall within 55 the scope of the appended claim.

What I claim is:—

A lamp of the class described comprising a water chamber and a carbide chamber, a water tube passing through the water chamber and into the carbide chamber, a valve at 60 the lower end of said tube, said valve having a triangularly shaped part formed integral with the valve, a valve stem passing through the water tube, means for bodily moving said stem and valve vertically to open and close the valve and independent means for 65 rotating said stem and valve horizontally to cause said triangular part to scrape the interior of the water tube.

In testimony whereof I affix my signature.

HENSON DAVIS.
